MERRY-GO-ROUND TOY

Duane E. Spengler, West Falls, N.Y., assignor to The
Quaker Oats Company, Chicago, Ill.

Filed Dec. 6, 1972, Ser. No. 312,592

Term of patent 14 years

Int. Cl. D21—01

U.S. Cl. D34—15 Q

FIG. 1 is a front perspective view of a merry-go-round toy showing my new design;

FIG. 2 is a rear elevational view thereof; and

FIG. 3 is a right-side elevational view thereof.

I claim:

The ornamental design for a merry-go-round toy, substantially as shown.
